UNITED STATES PATENT OFFICE.

GEORGE F. HENSEL, OF PHILADELPHIA, PENNSYLVANIA.

DESIGN FOR A HANDLE FOR SHADE-PULLS.

SPECIFICATION forming part of Design No. 23,713, dated October 23, 1894.

Application filed January 26, 1894. Serial No. 498,147. Term of patent 7 years.

To all whom it may concern:

Be it known that I, GEORGE F. HENSEL, a citizen of the United States, residing in Philadelphia, Pennsylvania, have invented a new

5 and original Design for the Handle of a Shade-Pull, of which the following is a specification.

My design for the handle of a shade pull is fully shown in the accompanying drawings, in which—

10 Figure 1, represents a side view of that portion of a shade pull embodying my design; and Fig. 2, is an end view of the same.

A represents part of the cylindrical and slightly tapering body or shank of the shade pull, which has, at the lower end, a bulb or protuberance B, with ornamental wrapping α of cord, and at the bottom of this bulb is a projecting jewel D of glass.

The essential feature of the design is the handle of a shade pull provided with the 20 jewel, D, projecting beyond a rounded or bulging end of the pull.

I claim—

The design for the handle of a shade pull, substantially as described and as shown in 25 the accompanying drawings.

In testimony whereof I have signed my name to this specification in the presence of two subscribing witnesses.

GEO. F. HENSEL.

Witnesses:

FRANK BECHTOLD,
JOSEPH H. KLEIN.
